UNITED STATES PATENT OFFICE.

EDWARD CHESHIRE, OF MILWAUKEE, WISCONSIN, ASSIGNOR, BY MESNE ASSIGNMENTS, TO MIEHLE PRINTING PRESS & MANUFACTURING COMPANY, OF CHICAGO, ILLINOIS, A CORPORATION OF ILLINOIS.

PRINTING PRESS.

Application filed March 25, 1918. Serial No. 224,426.

To all whom it may concern:

Be it known that I, EDWARD CHESHIRE, a citizen of the United States, and resident of Milwaukee, in the county of Milwaukee and State of Wisconsin, have invented certain new and useful Improvements in Printing Presses, of which the following is a specification.

This invention relates to printing presses and more particularly to cylinder printing presses.

One of the objects of this invention is to simplify the cylinder type of printing press, all of the principal motions being rotary or reciprocating or a combination of the two and the parts disposed in a manner whereby the same run in perfect balance at comparatively high speeds.

Another object is to make the various parts more accessible.

Another object is to transfer the stock from one part of the press to another in a novel and practical manner.

Another object is to control automatically, in an improved manner, the operation of the various parts of the press and to arrange the parts to cooperate in a given sequence to meet the various requirements for successful commercial use.

These and other objects are accomplished by the printing press disclosed in the following drawings, in which—

Figure 1 is a side elevation of a printing press, showing the cylinder in its highest position, where a sheet, after receiving an impression, is about to be taken from the cylinder by the delivery grippers;

Figure 2 is a side elevation from the opposite side, the parts being in the same relative position;

Figure 3 is a front elevation of the printing press;

Figure 4 is a rear elevation of the same press;

Figure 5 is a plan view of the press;

Figure 6 is a vertical sectional view of the printing press, taken in the planes of irregular lines 6—6 of Figure 5;

Figure 7 is another vertical sectional view of the press, showing the mechanism for opening and closing the cylinder grippers;

Figure 8 is a view similar to Figure 2

with portions removed and the transfer suction shoe in the position it occupies in taking a sheet from the pile or supply table;

Figure 9 is a front elevation, similar to Figure 3, with the supply table and associated mechanism removed from the press;

Figure 10 is an enlarged fragmentary side elevation of the transfer mechanism and some of the associated parts shown in the same position in which they appear in Figure 8;

Figure 11 is a fragmentary side elevation of the elevating mechanism for maintaining the paper or stock at a predetermined height;

Figure 12 is a fragmentary side elevation of associated parts, including the arm for connecting the supply or stock table mechanism to the cylinder frame of the press;

Figure 13 is a plan view of the transfer table, and also showing in dotted lines the associated end stop and cylinder grippers;

Figure 14 is a transverse section in the plane of line 14—14 of Figure 13;

Figure 15 is a detailed plan view of the suction shoe, by means of which stock is transferred from the stock table to the transfer table;

Figure 16 is a front elevation of the same suction shoe, shown in Figure 15, as indicated by the line 16—16 of Figure 15;

Figure 17 is a transverse vertical section taken in the plane of line 17—17 of Figure 16;

Figure 18 is a fragmentary side elevation parts being in section, of the mechanism for tripping the cylinder;

Figure 19 is a fragmentary vertical section through the inker frame, showing the mechanism for locking the inking rolls and their frame in operative position;

Figure 20 is an end view, parts being in section, of the cylinder;

Figure 21 is a longitudinal sectional view of an associated air pump;

Figure 22 is a vertical sectional view taken in the plane of line 22—22 of Figure 21;

Figure 23 is a detailed plan view of the valve for controlling the suction to the suction shoe, transfer table and cylinder trip mechanism;

Figure 24 is a view taken in the plane of the irregular line 24—24 of Figure 23;

Figure 25 is a transverse sectional view of the trip control for the cylinder, including a cylinder and piston, the latter of which is actuated by suction in one direction to cause the cylinder to move into a printing position, said piston being actuated positively in the opposite direction for maintaining the cylinder in a tripped position in the event that stock is not transferred to the transfer table, covering the suction holes thereof;

Figure 26 is an enlarged detail view of the delivery grippers;

Figure 27 is a detail view of part of the mechanism for controlling the upward movement of the stock table; and,

Figure 28 is a diagrammatic view of the air control system.

The various novel features of my invention will be apparent from the following description and drawings and will be particularly pointed out in the appended claims.

The main frame 10 of the printing press is provided with side members 11 and 12, which are connected by suitable integral transverse members 13. Mounted in and extending between the side frame members 11 and 12 is a cam shaft 14 carrying a gear wheel 15 keyed thereto, said gear wheel 15 being actuated by a pinion 16 mounted upon a shaft 17, which also carries a pulley 18 around which passes a belt 19 connected to a driving motor 20. Pivoted to the gear 15 and near its periphery is a connecting rod or link 21, one end of which is connected to an arm 22 keyed to a rock shaft 23, which extends between the side frame members 11 and 12. Secured to an intermediate portion of the rock shaft 23 is a bifurcated arm 24, to the outer end of which is pivotally connected a link 25, the upper end of which is pivotally connected to a type-bed 26, which carries a chase frame 27, the chase frame being secured to the type-bed in any suitable manner. Secured to the ends of the rock shaft 23 are arms 28, to the outer ends of which are pivoted links 29, which are pivoted at their upper ends to the cylinder frame 30.

Cylinder mechanism.

Rotatably mounted in the cylinder frame is the printing cylinder 31, which cooperates with the type for printing purposes, said cylinder being provided near one end with a gear wheel 32 which meshes with a rack 32^a carried by the type bed 26 and being slidably mounted in the main frame. By referring to Figure 20, it will be noted that this cylinder, among other things, is provided with grippers taking the form of plungers 33, the gripping heads 34 of which are normally

held within the confines of the periphery of the cylinder by spring 35. These grippers, there being any desired number, are positively opened by cranks 36 pivotally mounted upon a shaft 37. One arm of each of the cranks 36 has a roller 38' which is adapted to engage (see Figure 7) cams 38 and 39, arranged at the upper and lower limits of travel, respectively, of the cylinder upon a slide member 40, which is given a quick reciprocal movement by cam projections 41 and 42 on a disk 43 carried by the cam shaft 14. The cam projections 41 and 42 pass into engagement with a roller 44 mounted in the end of one of the arms of a crank 45 pivotally mounted at 46, the other arm 45 of the crank 45 being pivotally connected to the lower end of the slide member 40.

Inking mechanism.

Also carried by the cylinder frame (Figures 6 and 19) is an inker frame 47 pivotally connected to the former at 48. This inker frame carries inking rollers 49 and 50 and an ink distributing roll 51, one end of which is provided with a gear 52 (Figure 9), which meshes with a gear 53, which in turn meshes with the rack 32^a, whereby the ink distributing roll 51 is positively actuated for performing its function. Pivotally connected to the upper portion of the inker frame 47, is a spring pressed latch 54, by means of which the inker frame may be released to swing about its pivot 48 into its lower position, wherein the inker frame extends outwardly at right angles with respect to the cylinder frame. The inker frame is held in such position by its foot 55 engaging the cylinder frame. Located at the lower limit of travel of the inking rolls is the ink fountain 56 from which ink is supplied.

It will be noted that the type-bed is operatively connected to the rock shaft 23 at one side thereof and that the cylinder frame is operatively connected to the rock shaft 23 at the other side thereof. These oppositely arranged vertically and rectilinearly moving parts are balanced with respect to each other so that the same may be actuated at a high rate of speed and at all times run in perfect balance.

Feeder mechanism.

Extending forwardly from the main frame at one side thereof is an arm 57 (Figures 2 and 5), to the outer end of which is pivotally connected a feeder frame 58. When the press is to be operated, the feeder frame is locked to the main frame by a lock bar 66 (Figure 1), one end of which is pivotally connected to a bracket 67 carried by the feeder frame 58 and the other end of which lock bar is provided with a groove 68, which receives a stationary supporting pin 69

secured to the main frame. The extreme outer end of the lock bar rests upon a member 70 and is held in engagement therewith by a pivotally mounted lock member 71.

6 When it is desired to swing the feeder frame away from the main frame it is merely necessary to swing the locking member 71 out of a locking position and raise the lock bar 66, whereupon the feeder frame may be

10 swung. In this connection, however, it is to be noted that another member or arm 72 (see Figures 10 and 12) must be unlatched from the cylinder shaft 73 by depressing the spring-pressed latch 74, whereupon the

15 member 72 may be moved out of operative association with said cylinder shaft, thereby permitting the feeder frame to swing into a position to make the cylinder, inking rolls, chase frame and other parts accessible. This

20 feeder frame carries a stock table 59 (Figures 1, 2, 6, and 8), having a downwardly extending rack 60, which is raised by a gear 61 mounted upon a shaft 62 which also carries a ratchet wheel 63, (Figures 10 and 11)

25 cooperating with which are a holding pawl 64 and a stepping pawl 65, the latter of which is pivotally connected to arm 75 loose on the shaft 62. Pivotally connected to the outer end of the arm 75 is one end of a link

30 76, the other end of which has a laterally extending portion which is adapted to move in a slot 77 formed in the ear 78 of a casting 79 mounted on a shaft 80. To one arm 81 of the casting 79 is pivotally connected

35 one end of the link 72, the other end of which is pivoted to the cylinder shaft 73. From this arrangement it is apparent that as the cylinder 31 moves downwardly, the casting 79 will be rocked forwardly away from the

40 cylinder, thereby causing the rear end of link 76 to move downwardly in the slot 77 unless another element comes into play. This other element (see Figure 11) takes the form of a lever 82, which is pivotally

45 connected at 83 to an arm 84 connected to the supporting shaft 80. It will be noted (see Figure 10) that the arm 72 is provided with a downwardly extending projection 85, which is adapted to pass into engagement

50 with the rounded head 86 of an arm 87 mounted on the shaft 80, said arm 87 normally being held in its highest position by a spring 88, the upper end of which is secured to a hook 89 on the feeder frame 58. The

55 arm 87 also carries a spring-pressed plunger 90, to the upper end of which is pivotally connected a link 91 extending upwardly (see Figures 8 and 15) and connected to the front end of a sucker shoe 92 or feeder member at

60 the point 93. Links 94 parallel to the link 91 are connected at their upper ends to the sucker shoe 92 at points 95 and 96 and have their lower ends each connected to the casting 79. From the mechanism hereinabove

65 described it will be seen that when the cylinder 31 is moved into its lowermost position, as shown in Figures 8 and 10, the arm 72 causes the sucker shoe to move into a position over the stock or paper carried by the stock table 59 and causes the projection 85 to pass into engagement with the arm 87 in a manner to depress the same, thereby causing the link 91, through the spring-pressed plunger 90 to move the front portion of the sucker shoe down into engagement with the top sheet of paper or stock carried by the stock table. If the top sheet of the stock on the stock table is at a maximum predetermined height, the sucker shoe 92 will be given a minimum dip and in view thereof the spring of the spring-pressed plunger 90 will be compressed a maximum amount, as the arm 87 is depressed. Under such conditions not only is the link 91 drawn down a minimum amount, but also the same is true with respect to the plunger 90, and, therefore, the plunger head (Figure 27), which is enlarged a sufficient amount to pass into engagement with the short arm of the lever 82 when the plunger is depressed a certain amount. When the short arm of the lever 82 is not engaged by the head of plunger 90, the longer arm of the lever 82 remains out of engagement with the loose end of link 76, thereby permitting the loose end of said link to move up and down in the slot 77, as the member 79 is rocked back and forth by the action of link 72 in accordance with the rising and falling movement of the cylinder 31. When the free end of the link 76 is free to move back and forth in the slot 77, no motion, or only a slight motion, is transmitted to the arm 76 and therefore the stepping pawl 65 is not given a large enough throw to cause the ratchet wheel 63 to be actuated for raising the stock table 59. However, as the stock on the stock table 59 is gradually reduced in height, the dip of the sucker shoe 92 is increased and causes the enlarged head of the plunger 90 to pass into engagement with the short arm of lever 82 to lift the longer arm of lever 82 into a position to limit the travel of the free end of link 76 in the slot 77. Under these conditions the throw of arm 75, and therefore the travel of the stepping pawl 65, is increased when the stock on the stock table has been decreased in height a given amount. For example, when one-eighth of an inch of stock is removed from the table, the dip of the sucker shoe 92 will increase to such an extent that the plunger 90 will move downwardly a corresponding amount and therefore the head of the plunger will engage the shorter arm of lever 82 in a manner to force the longer arm of lever 82 into a position to hold the free end of lever 76 in the upper portion of the slot 77, whereby the stepping pawl 65 will travel a sufficient amount to engage the next notch on

the ratchet wheel 63 and cause the ratchet wheel 63 to rotate a given increment, thereby rotating the gear 61 to raise the rack 60 and thereby the stock table 59 to raise the stock thereon to the original predetermined height. In this way stock on the stock table is maintained at substantially a constant height, the variation in height being compensated for by the mechanism hereinabove particularly described. In each case the sucker shoe is given sufficient dip to pass into engagement with the top sheet of stock. The function thereof will be considered hereinafter.

15 *Transfer mechanism*

The paper or other stock to be printed is transferred or fed from the stock table to a transfer table 97 by the sucker shoe 92 and 20 and from the transfer table to the cylinder 31. This transfer table 97 (Figures 6 and 13) is mounted on a frame 98 having arms 99, pivotally connected at 100 to the feeder frame 58.

25 Referring particularly to Figure 13, it will be noted that the frame 98 is provided with a plurality of obliquely arranged slots 101, which receive downwardly extending projections 102 on the transfer table 97. 30 From this arrangement it is apparent that if the transfer table 97 is given a transverse movement toward one side of the machine, it will move forwardly and laterally toward the cylinder 31. Its return movement will 35 be rearwardly and laterally away from the cylinder, the last movement being accomplished by means of springs 103. The transfer table 97 is given its forward and lateral movement toward the cylinder 31 by a

40 spring-pressed plunger 104 (Figures 2 and 9), which under certain conditions is forced into engagement with the member 105 secured to the one corner of the transfer table. This spring pressed plunger is carried by the cylinder frame 30, and when this cylinder frame reaches its lower limit of movement the plunger 104 comes into registry with a member 106 (Figure 5) mounted upon one end of a lever 107, pivoted at 108, 45 the other end of said lever being pivotally connected to a link 109, which in turn is connected to a lever 110 (Figure 4) pivotally supported intermediate its ends at the point 111 and having at its free end a roller 112

50 lying within the path of movement of a cam projection 113 on the disk 114 mounted upon the cam shaft 14. From this arrangement it is apparent that when the cam projection 113 operates the lever 110, the spring-pressed plunger 104 is forced into engagement with the transfer table 97 for shifting the same laterally and forwardly toward the cylinder. The real function for shifting the transfer table 97 laterally and forwardly is 55 to carry a sheet of paper or other stock into

engagement with a side stop member 115 (Figures 9 and 13), which is also carried by the cylinder frame in order that the paper or other stock may be properly registered or positioned with respect to the cylinder and 70 the type. During the first part of this transverse movement of the transfer table, the suction at the table is cut off, thereby releasing the stock. During continued movement of the table, the sheet of stock, due to its own weight or frictional engagement with the table, is moved into engagement with the side stop and cylinder grippers and thereby brought into register. The table continues 75 its movement in the same direction even after the stock is registered to positively obtain proper registering and maintain the stock in register until actually gripped by the cylinder grippers.

80 The transfer table and its frame rest upon the cylinder frame 30 and follow the rising and falling movement thereof. In order to prevent the sheet of paper or other stock from flying off of the transfer table 97 as it is lowered, the paper is retained in position on the table 97 by air suction which is extended up through suitable openings 116 (Figure 13) in the table, said openings leading from an air tight chamber 117 secured to the lower side of the table 97 and having a communication with two air hose or conduits 118 and 119 which are operatively associated with a source of vacuum to be referred to later. At the time that the table 97 is shifted laterally and forwardly toward the cylinder, it is appreciated that the air connection or the pipe sections which are in butt relationship will be broken at the points 120, whereupon the sheet of paper or other stock is no longer positively held on the 100 table 97. At the time that the vacuum holding effect on the sheet of stock is released, the sheet of stock is then immediately thereafter properly aligned or registered and placed in engagement with the cylinder 105 grippers 33, which are momentarily opened and closed by the mechanism hereinabove described, whereupon the sheet of stock is wrapped around the cylinder as the latter 110 is given its upward movement, during which time the stock receives the impression or printing, the type at the same time moving downwardly.

115 By referring to Figures 15, 16, and 17, it will be noted that the under part of the 120 suction shoe is provided with two air chambers 121 provided with suction holes 122. A suction is extended through the conduit 123 from a suitable source to be referred to hereinafter, whereby at predetermined intervals, such, for example, when the suction shoe is dipped down into engagement with the top sheet of stock, the latter is drawn or picked up and transferred to the transfer 125 table. When the stock is transferred to the 130

transfer table, the effective suction at the suction shoe 92 is rendered ineffective by means to be considered later.

5 *Cylinder tripping mechanism.*

When the cylinder 31, which has a vertically rectilinear movement, reaches its upper limit, it is tripped so that the same may be moved downwardly out of engagement with the type. Means is provided for moving the cylinder back into engagement with the type at its lower limit of movement preparatory to the next upward movement of the cylinder. This means includes (referring to Figures 1, 9 and 18) a rack bar 124 slidably mounted in a casing 125 carried by the cylinder frame. The lower part of this rack bar extends out of the casing 125, and when the same has been moved downwardly 10 with the cylinder and cylinder frame to a point adjacent the lower extreme limit of movement of the cylinder, the rack bar 124 engages with a stop member 126, whereby the rack bar 124 as such continues its downward movement and rises in its casing, thereby causing its cooperating gear 127 to rotate in a clockwise direction. In view of the fact that this gear has a pin 128 journaled in a block 129 slidably mounted in the guide 15 arm 130, upon clockwise rotation of the gear 127 the block is caused to slide inwardly with respect to the guide arm 130, causing at the same time a downwardly turning movement of the guide arm 130. In view of the fact that the pivotal center 131 of the guide arm 130 is eccentric with respect to the center 132 of the cylinder, the cylinder 31 is swung into a position where it will engage the type for the next upward movement. 20 Let it be assumed that a sheet of paper or other stock has been gripped by the cylinder grippers and that the cylinder has been moved to a position where it will engage the type for printing purposes, preparatory to the upward movement of the cylinder. Cylinder 31 with its frame and other associated parts is moved upwardly. When the cylinder reaches its upward limit of movement, or substantially so, the stock having been 25 printed, the upper extended end of the rack bar 124 passes into engagement with a stop 133 (Figure 1) secured to the main frame, causing the rack bar as such to discontinue its upward movement and on the other hand to be moved downwardly in its casing, thereby causing its associated gear 127 to rotate in a counterclockwise direction, causing the block 129 to slide outwardly in the arm 130 and rocking the cylinder 31 to a position where it will not engage the type on the next downward movement of the cylinder. The cylinder is locked in both its in and out positions with respect to the type because of 30 the location of centers.

It is when the cylinder has reached its upper limit of movement that (see Figure 1) the sheet of stock is removed from the cylinder by delivery grippers 134 to be referred to later. At the same time it will be noted 70 that the suction shoe has carried another sheet of paper from the stock table 59 onto the transfer table 97. Just at the moment that a sheet of stock is deposited upon the transfer table 97, the suction openings 116 75 therein are covered, causing the paper or stock to be held on the transfer table, it being understood that the suction extending to the transfer table at this time is controlled by means to be referred to later. 80

At the moment that the sheet of stock covers the suction openings 116 on the transfer table 97, a suction is produced (see Figure 25) on the stop member side of the piston 135, movably mounted in the cylinder 136, which is secured to the main press frame, whereby the stop 126 is moved into the path of movement of the rack bar 124. This stop member 126 must lie in the path of movement of the rack bar 124 so that when 90 the cylinder reaches a point adjacent its lower limit of movement the cylinder may be moved from a tripped position into a printing position.

It will be noted that when the cylinder is 95 moved upwardly into the upper position, a cam projection 137 (Figures 9 and 25) mounted on the cylinder frame forces the stop member 126 inwardly out of the path 100 of movement of the rack bar 124 for the purpose of preventing the cylinder from moving into printing position the next time the cylinder reaches its lower limit of movement, unless a sheet of stock has been transferred to the transfer table and covers the 105 suction openings 116.

Delivery mechanism.

Referring now more particularly to the delivery grippers 134 (see Figures 1, 2 and 26), it will be noted that each of the grippers includes an upper relatively stationary jaw 138 and a lower relatively movable spring jaw 139, the rear end of which is clamped to the rear portion of the stationary jaw 138. Mounted in the stationary jaw 138 is a pin 140 carrying a projection 141, which when rotated downwardly depresses the spring jaw 139 in a manner to open the gripper for receiving the sheet of stock from the cylinder 31 preparatory to transferring the same to the receiving table or jogger 142. The stationary gripper jaw 138 is mounted upon an arm 143, the lower end of which is secured in a casting 144 (Figures 6 and 7) mounted upon a supported shaft 145, said casting having a downwardly and rearwardly extending arm 146, having a guideway for the reception of a sliding block 147 (see Figure 6) having a pin 148 movable in the 115 120 125 130

cam groove 149 carried by disk 150. By means of this arrangement the grippers as a whole are reciprocated back and forth between the cylinder 31 and the receiving table 142. In connection with the opening and closing of the grippers, attention is called to the fact that secured to the pin 140 in the stationary jaw 138 of the grippers is an arm 151, to which is pivoted a link 152, the lower end of which is pivoted to a bell crank lever 153 having in the end of one of its arms a roller 154 lying in the path of movement of a cam projection 155, which is arranged to open the grippers or to give the lower spring jaws 139 thereof a quick opening movement for gripping a sheet of stock to be delivered from the cylinder 31 to the receiving table 142. As the delivery grippers are moved to a point over the receiving table 142 they are opened again for delivering the impressed sheet thereon. To this end the movable gripper jaw 139 is given an opening movement as a result of a roller 159 mounted on arm 152 passing further under and thereby being lowered by the cam ledge 158 on a sector 157 which is arranged adjacent the arm 152. By referring to Figures 6 and 7 the sector 157 and its cam ledge 158 and roller 159 can be seen, the shape of the cam ledge 158 itself being best shown in Figure 7. As the delivery grippers are moved from the receiving table toward the cylinder 31 the cam ledge 158 permits the lower gripper jaw 139 to close prior to another opening movement thereof caused by the cam projection 155. If it is desired to vary the effective throw of the delivery grippers, this may be accomplished by adjusting a screw member 156 which is operatively connected to the sector 157; the position and operative effect of the cam ledge 158 in opening the grippers over the table 142 thereby being changed.

Air system.

The air system associated with this printing press includes a cylinder 160 (Figures 21 and 22), in which a piston 161 is operated through a pitman 162 connected to the crank shaft 17 (Figure 7). To the outer end of the cylinder 160 is connected a compression chamber 163 and a vacuum chamber 164, said chambers being separated by a central partition 165. The cylinder 160 has communication with the compression chamber 163 through openings 166 in a wall 170, said openings normally being closed by leaf springs 167. The springs are arranged on the inside of the compression chamber, so that air or other fluid may be pumped into said compression chamber and prevented from backward movement to the cylinder 160. The cylinder 160 has communication with the vacuum chamber through openings 168, which normally are covered by leaf

springs 169 mounted on the cylinder side of the dividing wall 170, whereby air or other fluid may be drawn from the vacuum chamber into the cylinder 160. Pressure regulating valves 171 are provided for the compression and vacuum chambers. The compression chamber 163 is connected by a pipe or conduit 172 to three vertically arranged blowers 173 for separating the top sheet of stock from the balance of the pile to facilitate the withdrawing action of the suction shoe 92. Connected to the vacuum chamber 164 is a suction conduit 174 connected to a valve chamber 175, which is secured to one side of the press main frame. Leading from this valve chamber 175 (Figure 28) is a vacuum conduit 176 which extends through various connections to the suction chambers 121 carried by the suction shoe 92. Also leading from the valve casing 175 is the vacuum conduit 119, which is connected with the suction chamber 117 (Figure 13) in the transfer table 97. The suction conduit 118 leading from the suction chamber 117 is connected with the suction side 177 of the cylinder control piston or diaphragm 135 (Figure 25), by means of which right angle movement of the cylinder relative to the type is controlled. Movably mounted in the valve chamber 175 (Figure 24) is a valve stem 178 having two valves 179 and 180. As shown in Figure 24, valve 180 is seated and valve 179 is in an open position, whereby there is an effective suction extending through the conduit 119 to the suction chamber 117 of the transfer table 97 and from there to the suction side 177 of the piston 135. With valve 180 in this position, atmospheric air enters conduit 176 to overcome any residual effect of vacuum therein. The position of the corresponding parts at this time is shown in Figure 2. It will be noted that the cylinder 31 is in its upper position and the transfer table 97, which rests upon the cylinder frame, is also in its upper position. As the cylinder moves downwardly, the transfer table therefor also moves downwardly, the stock on said transfer table being held thereto by the suction thereon. At the same time the piston 135 (Figure 27) causes the stop 126 to move outwardly into the path of movement of the rack bar 124, so that when the cylinder 31 approaches its lower limit of movement, said cylinder will be moved towards the type. When the cylinder reaches its lower position it no longer is necessary for the suction to hold the stock on the transfer table 97, and accordingly a projection 181 (See Figure 2), carried by the cylinder frame, passes into engagement with the upper end of the valve stem 178 to move valve 179 into a closed position and valve 180 into an open position, whereupon suction is extended through the conduit 176 to the suction shoe 92, which by this time is

in the position shown in Figure 8, to pick up another sheet of stock, which it does, and by the time that the cylinder 31 has been moved to its upper limit, as shown in Figure 2, the suction shoe 92 has completely transferred the stock from the stock table to the transfer table 97. At the same time, with valve 179 seated against suction, atmospheric air enters conduit 119 to overcome any residual effect of vacuum therein. There is no longer any need for the suction shoe to retain the stock, therefore the suction is cut off from the suction shoe by the action of a cam 182 (Figure 2), which moves in the path of and operates a lever 183 pivoted intermediate its ends at 184 and to one end of which is connected the valve stem 178, causing the valve 180 to be moved into a closed position to cut off the suction at the suction shoe 92 and to move the valve 179 into an opened position, whereupon suction will be extended to the transfer table and to the control mechanism shown in Figure 25. At this point it might be stated again that the stop member 126 is moved out of the path of movement of the rack 124 by the cam projection 187 carried by the cylinder frame when the cylinder is moved into its upper position. Accordingly, the stop member 126 will not again be drawn out into the path of movement of the rack 124 until a sheet of stock has covered the suction openings 116 of the transfer table 97. Therefore, it is impossible to force the cylinder 31 into engagement with the type unless stock has been supplied to the transfer table, or unless it is accomplished manually by pushing on a member 126^a connected to the piston 135.

The general operation of the machine, in brief, is as follows: Let it be assumed that the parts are in the position shown in Figure 8. In this position, the stock on the table being at the proper height, the suction shoe 92, which at this time is provided with suction, in effect grips a piece of stock and through the mechanism hereinabove described carries the sheet of stock to the transfer table 97 as the latter, through the upward movement of the cylinder, assumes a position shown in Figure 2 of the drawings, at which time the suction at the shoe is cut off and the suction on the transfer table is cut in and the stop member 126 is drawn into the path of movement of the rack bar 124, it being appreciated that during the upward movement of the cylinder a piece of stock previously received by the cylinder was being printed. Just at the moment the cylinder 31 reaches its upper limit its grippers release their hold through mechanism hereinabove described, and the delivery grippers take hold of the printed stock preparatory to transferring the printed stock to the jogger 142 during a continued operation of the machine. Also when the cylinder 31 is approaching its upper limit of movement, said cylinder is caused to move away from the type by mechanism above described, whereby, upon the downward movement of the cylinder, the latter will not bear upon the type. When the cylinder approaches its lower limit of movement, the suction is cut from the transfer table, and substantially at the same time the transfer table is shifted laterally and toward the cylinder to place the stock in alignment with the cylinder. At the instant the paper is properly aligned or registered, the grippers of the cylinder grip the stock preparatory to an upward movement of the cylinder, during which time the stock is printed. At this point, it might be stated that the transfer table is provided with a retaining member 186 (Figures 13 and 14), whereby the stock is guided directly into the cylinder grippers and prevented from moving into a position such that the grippers are not in range of the sheet. This retaining member 186 is raised from its normal position by a cam projection 187 (Figure 17) on the suction shoe 92 at the time that the latter deposits stock on the transfer table.

The operation of the printing press throughout is automatic from the time the stock is placed on the supply or feed table until the printed stock is received by the jogger. Of course, it is appreciated that the stock may be fed manually if desired. By means of movably connecting the feeder frame to the main frame of the press, the former may be moved away from its normal operative position for "make-ready", and it is a simple matter to swing or otherwise move the stock frame and feeder back into its normal operative position with respect to the main frame and connect the operative parts carried by both of said frames in a minimum amount of time.

When the cylinder approaches its lower position of dwell, the suction shoe picks up a sheet of stock from the stock table, the latter is elevated if the stock thereon is reduced a given amount, the cylinder is moved into printing engagement with the type, the suction is cut from the transfer table, the stock thereon aligned with the cylinder, the stock on the transfer table is gripped by the cylinder grippers. When the cylinder approaches its upper position of dwell, the cylinder is released, suction is cut from the suction shoe, a sheet of stock placed on the transfer table, suction applied to latter, cylinder grippers released, and an impressed sheet of stock on cylinder gripped by delivery grippers. All these actions are automatic.

It is apparent that there may be various modifications of the invention herein par-

ticularly shown and described, and it is my intention to cover all such modifications falling within the spirit and scope of the following claims.

5. What I claim as new is:

1. In a printing press, the combination of stock supply means, a cylinder mounted for vertical rectilinear movement, a transfer table movable upwardly and downwardly 10 with said cylinder, and means for transferring stock from said stock supply means to said transfer table.

2. In a printing press, the combination of stock supply means, a cylinder mounted for vertical rectilinear movement, a transfer table movable upwardly and downwardly 15 with said cylinder, and means for automatically transferring stock from said stock supply means to said transfer table.

20 3. In a printing press, the combination of a stock table, a cylinder mounted for vertical rectilinear movement and which rotates as an impression is made, and means for transferring stock from said table to said cylinder.

4. In a printing press, the combination of a stock table, a vertically movable cylinder which rotates as an impression is made, and means for automatically transferring 25 stock from said table to said cylinder.

5. In a printing press, the combination of stock supply means, vertically movable printing means having a rotary motion when an impression is made, and means intermediate said stock supply means and printing means for receiving stock transferred from said stock supply means.

40 6. In a printing press, the combination of stock supply means, a printing couple including a substantially vertically arranged vertically movable type bed, and transfer means functioning intermediate said stock supply means and printing couple.

45 7. In a printing press, the combination of stock supply means, a printing couple including a substantially vertically arranged vertically movable type bed, and a transfer member movable between said stock supply means and printing couple.

50 8. In a cylinder type of printing press, the combination of stock supply means, a printing cylinder, and pivotally mounted means intermediate said stock supply means and printing cylinder whereby stock is automatically transferred from one to the other.

60 9. In a printing press, the combination of stock supply means, a reciprocating printing cylinder, and single means for removing a piece of stock from its normal piled condition on said stock supply means and moving the same toward the printing cylinder, the movement of said single means being controlled by said printing cylinder.

10. In a printing press, the combination

of stock supply means, a vertically movable 65 printing cylinder, and single means for removing stock from said stock supply means and progressively moving the same during an upward movement of said cylinder.

11. In a printing press, the combination 70 of stock supply means, a vertically movable printing cylinder, and single means for automatically moving stock from said stock supply means and moving the same toward the cylinder during an upward movement of the 75 latter.

12. In a printing press, the combination of stock supply means, a vertically movable cylinder, means for receiving stock from said stock supply means, and means for transferring stock from said stock supply means to said stock receiving means during an upward movement of said cylinder.

13. In a printing press, the combination of stock supply means, a vertically movable 85 printing cylinder, stock receiving means intermediate said stock supply means and printing means, and means for transferring stock from said stock supply means to said stock receiving means during an upward 90 movement of said cylinder.

14. In combination, stock supply means, a vertically movable printing cylinder, and transfer means movable up and down with said cylinder for receiving stock from said stock supply means and registering stock with respect to said cylinder during downward movement of said cylinder.

15. In combination, stock supply means, rectilinearly movable printing means, and 100 automatically-controlled transfer means movable up and down with said printing means for receiving stock from said stock supply means and registering stock with respect to said printing means.

16. In a cylinder type of printing press, the combination of stock supply means, a vertically movable transfer table for receiving stock from said stock supply means, and means for feeding stock from said stock supply means to said transfer table during a given movement of the latter.

17. In a cylinder type of printing press, the combination of stock supply means, a vertically movable transfer table for receiving stock from said stock supply means, and means for automatically feeding stock from said stock supply means to said transfer table during an upward movement of the latter.

18. In a cylinder type of printing press, the combination of stock supply means, a vertically movable transfer table, and means for feeding stock from said stock supply means towards said transfer table during an upward movement of the latter.

19. In a cylinder type of printing press, the combination of a stock table, a transfer

table mounted for vertical movement with the cylinder as the latter moves rectilinearly, and means for feeding stock from said stock supply table to said transfer table during movement of the latter.

20. In a cylinder type of printing press, the combination of a stock table, a transfer table mounted for vertical movement with the cylinder as the latter moves rectilinearly, and means for automatically feeding stock from said stock table towards said transfer table during movement of the latter.

21. In a printing press, the combination of a stock table, a cylinder mounted for rectilinear movement, and a transfer table therewith and to which stock is supplied from said stock table and from which the same is supplied to the cylinder.

22. In a printing press, the combination of stock supply means, a printing couple including a substantially vertically arranged vertically movable type bed, a transfer table from which sheets are passed to the printing couple, and means for transferring sheets from said stock supply means to said transfer table.

23. In a printing press, the combination of a stock table, a cylinder mounted for a rectilinear movement, a transfer table intermediate said stock table and the cylinder and movable with the latter, and means whereby stock transferred from said stock supply table to said transfer table is registered with respect to said cylinder.

24. In a printing press, the combination of a stock table, a cylinder mounted for a rectilinear movement, a transfer table movable therewith, means for transferring stock from said stock table to said transfer table, and means for moving said transfer table for registering stock with respect to said cylinder.

25. In a printing press having a cylinder mounted for rectilinear movement, the combination of stock supply means, a movably mounted transfer table movable with and independent of said cylinder, and means for transferring stock from said stock supply means to said transfer table.

26. In a printing press, the combination of stock supply means, a cylinder mounted for rectilinear movement, a pivotally mounted transfer table movable with said cylinder, and means for depositing stock from said stock supply table to said transfer table at the upper limit of movement of the latter.

27. In a printing press, the combination of stock supply means, a cylinder mounted for a rectilinear movement, and transfer means therebetween movable in different directions with said cylinder.

28. In a printing press, the combination of a frame, a stock carrying frame movably mounted with respect thereto, a stock table adjustably mounted in said stock carrying

frame, a movable feed gripper adapted to engage the top sheet on said stock table, operative parts carried by both of said frames, an operative connection between said parts whereby said stock table may be automatically adjusted when said feed gripper is given a predetermined movement, and means whereby said operative connection may be moved out of association with the operative parts of one of said frames to permit a relative movement between said frames.

29. In a printing press, the combination of a frame, a stock carrying frame movably mounted with respect thereto, a stock table the position of which may be changed in said stock carrying frame, a movable feed gripper adapted to engage the top sheet on said stock table, operative parts carried by both of said frames, an operative connection between said parts whereby said stock table may have its position automatically changed when said feed gripper is given a predetermined movement, means whereby said operative connection may be moved out of association with the operative parts of one of said frames to permit a relative movement between said frames, and a locking connection between said frames for holding said frames rigid for operating conditions.

30. In a printing press, the combination of stock carrying means, vertical rectilinearly movable printing means, and transfer means movable between said stock carrying means and printing means controlled by the vertical movement of said printing means for withdrawing stock from said stock carrying means.

31. In a printing press, the combination of stock carrying means, bodily movable printing means, and transfer means movable between said stock carrying means and printing means automatically controlled by the movement of said printing means for withdrawing stock from said stock carrying means.

32. In a printing press, the combination of stock carrying means, a bodily movable printing cylinder, and a feed gripper movable between said stock carrying means and printing cylinder controlled by movement of said printing cylinder.

33. In a printing press, the combination of stock carrying means, a vertically movable printing cylinder, a feed gripper, and means whereby said feed gripper is moved toward said stock carrying means by a given movement of said printing cylinder.

34. In a printing press, the combination of stock carrying means, a vertically movable printing cylinder, a feed gripper, and means whereby said feed gripper is moved toward said stock carrying means by a downward movement of said printing cylinder.

35. In a printing press, the combination

of stock carrying means, a bodily movable printing cylinder, a feed gripper, and means whereby said feed gripper may be moved away from said stock carrying means by a given movement of said printing cylinder.

36. In a printing press, the combination of stock carrying means, a vertically movable printing cylinder, a feed gripper, and means whereby said feed gripper may be moved away from said stock carrying means by an upward movement of said printing cylinder.

37. In a printing press, the combination of stock carrying means, a vertically movable printing cylinder, a feed gripper, and means whereby said feed gripper is moved toward said stock carrying means during a downward movement of said printing cylinder and away from said stock carrying means during an upward movement of said printing cylinder.

38. In a printing press, the combination of stock carrying means, a printing cylinder mounted for bodily movement, a transfer table movable therewith, and means for transferring stock from said stock carrying means to said transfer table during a given movement of said printing cylinder and transfer table.

39. In a printing press, the combination of stock carrying means, a printing cylinder mounted for vertical rectilinear movement, a transfer table movable therewith, and means for transferring stock from said stock carrying means to said transfer table during an upward movement of said printing cylinder and transfer table.

40. In a printing press, the combination of stock carrying means, a printing cylinder mounted for a vertical rectilinear movement, a transfer table, and means for transferring stock from said stock carrying table to said transfer table and giving the latter an upward movement during an upward movement of said printing cylinder.

41. In a printing press, the combination of stock carrying means, a printing cylinder mounted for a vertical rectilinear movement, a transfer table, and means whereby stock may be transferred from said stock carrying means to said transfer table and for giving the latter an upward movement during an upward movement of said printing cylinder and for giving said transfer table a downward movement during a downward movement of the printing cylinder.

42. In a printing press, the combination of stock carrying means, a bodily movable printing cylinder, and feed means connected to the printing cylinder whereby the feed means carries stock away from said stock carrying means toward the printing cylinder during a given movement of said printing cylinder.

43. In a printing press, the combination

of stock carrying means, a printing cylinder, and feed means connected to the printing cylinder whereby the feed means carries stock away from said stock carrying means toward the printing cylinder during an upward movement of said printing cylinder.

44. In a printing press, the combination of stock carrying means, a bodily movable printing cylinder, and feed means operatively connected to said printing cylinder whereby the feed means will be given a movement toward said stock carrying means during a given movement of said printing cylinder.

45. In a printing press, the combination of stock carrying means, a printing cylinder, and feed means operatively connected to said printing cylinder whereby the feed means will be given a movement toward said stock carrying means during a downward movement of said printing cylinder.

46. In a printing press, the combination of stock carrying means, a printing cylinder having a plurality of movements, and feed means operatively connected with the printing cylinder whereby the feed means will move from the stock carrying means toward the printing cylinder during one movement of said printing cylinder and away from said printing cylinder toward said stock carrying means during another movement of said printing cylinder.

47. In a printing press, the combination of stock carrying means, a vertically movable printing cylinder, means for withdrawing stock from said stock carrying means, and means controlled by said cylinder whereby the withdrawing means operatively engages the stock at the time when the printing cylinder is at a limit of movement.

48. In a printing press, the combination of stock carrying means, a vertically movable printing cylinder, means operable between said stock carrying means and printing cylinder for transferring stock, and means controlled by said cylinder whereby the transferring means operatively engages the stock at a limit of movement of said printing cylinder.

49. In a printing press, the combination of stock carrying means, a bodily movable printing cylinder, means for withdrawing stock from said stock carrying means, and means, associated with the printing cylinder whereby the withdrawing means operatively engages the stock during a given period in movement of the printing cylinder.

50. In a printing press, the combination of stock carrying means, a bodily movable printing cylinder, and means operable between said stock carrying means and printing cylinder for conveying stock and associated with the printing cylinder whereby the conveying means operatively engages the

- stock during a given period in movement of said printing cylinder.
51. In a printing press, the combination of stock carrying means, a printing cylinder mounted for vertical movement, means for feeding stock toward said printing cylinder, and means for withdrawing printed stock therefrom at a limit of movement of said printing cylinder.
52. In a printing press, the combination of stock carrying means, a printing cylinder mounted for vertical movement, means for feeding stock toward said printing cylinder and for withdrawing printed stock therefrom during a given period in the movement of said printing cylinder.
53. In a printing press, the combination of stock carrying means, a printing cylinder mounted for rectilinear movement, means separate from said cylinder for gripping the stock on said stock carrying means and means for withdrawing printed stock from said printing cylinder when the printing cylinder is at one limit of movement.
54. In a printing press, the combination of stock carrying means, a printing cylinder mounted for rectilinear movement, means separate from said cylinder for gripping stock on said stock carrying means and for withdrawing printed stock from said printing cylinder during given periods in the movement of said printing cylinder.
55. In a printing press, the combination of stock carrying means, a printing cylinder mounted for rectilinear movement, a transfer table movable therewith, means for transferring stock from said stock carrying means to said transfer table, and means whereby the stock is gripped at said stock carrying means during one dwell in movement of said printing cylinder and passed into engagement with said transfer table during another dwell in movement of said printing cylinder.
56. In a printing press, the combination of stock carrying means, a printing cylinder mounted for rectilinear movement, a transfer table movable therewith, means for transferring stock from said stock carrying means to said transfer table, means whereby the stock is gripped at said stock carrying means during one period in the movement of said printing cylinder and passed into engagement with said transfer table during another period in the movement of said printing cylinder, and means for withdrawing printed stock from said printing cylinder during one period in the movement of said printing cylinder.
57. In a printing press, the combination of stock carrying means, a printing cylinder mounted for rectilinear movement, a transfer table movable therewith, and means for gripping stock at the stock carrying means when the printing cylinder is at its lower limit of movement and for transferring stock from said stock carrying means to said transfer table during upward movement of said printing cylinder.
58. In a printing press, the combination of stock carrying means, a printing cylinder mounted for rectilinear movement, a transfer table movable therewith, means for gripping stock at the stock carrying means when the printing cylinder is at its lower limit of movement and for transferring stock from said stock carrying means to said transfer table during upward movement of said printing cylinder, and means for withdrawing printed stock from said printing cylinder at the upper limit of movement of said printing cylinder.
59. In a printing press, the combination of stock carrying means, a printing cylinder mounted for rectilinear movement, a transfer table movable therewith, means for gripping stock at the stock carrying means when the printing cylinder is at its lower limit of movement and for transferring stock from said stock carrying means to said transfer table during upward movement of said printing cylinder, means for withdrawing printed stock from said printing cylinder at the upper limit of movement of said printing cylinder, and means whereby the stock on said transfer table is engaged by said printing cylinder at the lower limit of movement of said printing cylinder.
60. In a printing press, the combination of stock carrying means, a bodily movable printing cylinder, a transfer table movable with the cylinder for receiving stock from said stock carrying table, and means for holding stock on said transfer table during a movement of the latter.
61. In a printing press, the combination of stock carrying means, a bodily movable printing cylinder, a transfer table movable with the cylinder, means for transferring stock from said stock carrying means to said transfer table, and means for preventing displacement of said stock on said transfer table during movement of the latter.
62. In a printing press, the combination of printing means, transfer means mounted for up and down movements and also a registering movement, means for retaining stock on said transfer means during down movement thereof, and means for releasing said retaining action prior to the time the stock is registered with said printing means.
63. In a printing press, the combination of printing means, a transfer table mounted for up and down movement and also a registering movement, means for retaining stock on said transfer table during one movement thereof, and means for releasing said retaining action when the stock is brought into operative association with said printing means.

64. In a printing press, the combination of printing means, grippers carried thereby, a transfer table having an up and down movement for supplying stock to said printing means, means for holding stock on said transfer table during a movement thereof, and means for liberating said stock just prior to the time the latter is registered with respect to the printing means and gripped by said grippers.

65. In a printing press, the combination of printing means, grippers carried thereby, a transfer table movable up and down for feeding stock to said printing means, means for holding stock on said transfer table during a movement thereof, and means whereby the stock is released from said holding means and gripped by said grippers.

66. In a printing press, printing means mounted for vertical movement, stock receiving means movable therewith, means for holding a sheet of stock thereon during a down movement thereof, means releasing said holding action, and means for moving said receiving means and sheet of stock together and independently of each other for registering the latter with respect to said printing means.

67. In a printing press, printing means, stock conveying means for carrying a sheet of stock in a vertical direction, and means for moving the stock conveying means laterally, the sheet of stock moving with the conveying means until brought into register with the printing means.

68. In a printing press, printing means, stock conveying means for carrying a sheet of stock in a vertical direction, and means for moving the stock conveying means laterally, the sheet of stock moving with the conveying means until brought into register with the printing means while the conveying means continues its movement.

69. In a printing press, printing means, stock carrying means for carrying a sheet of stock in a vertical direction, and means for moving the stock carrying means laterally, the sheet of stock moving with the carrying means due to frictional engagement therewith until brought into register with said printing means.

70. In a printing press, printing means, stock carrying means for carrying a sheet of stock in a vertical direction, and means for moving the stock carrying means laterally, the sheet of stock moving with the carrying means due to frictional engagement therewith until brought into register with said printing means while the carrying means continues its movement.

71. In a printing press, printing means having gripper means, stock carrying means for carrying a sheet of stock in a vertical direction, and means for moving the stock carrying means laterally, the sheet of stock

moving with the carrying means until it comes into register with said printing means and gripped by said gripper means.

72. In a printing press, printing means having gripper means, stock carrying means for carrying a sheet of stock in a vertical direction, and means for moving the stock carrying means laterally, the sheet of stock moving with the carrying means until it comes into register with said printing means and gripped by said gripper means while the carrying means continues its movement.

73. In a vertical type of printing press, the combination of vertically and oppositely movable type bed and cylinder, and a transfer table movable with said cylinder.

74. In a printing press, the combination of a vertical rectilinearly movable printing cylinder, and a transfer table movable therewith.

75. In a printing press, the combination of a vertical rectilinearly movable printing cylinder, and transfer means movable therewith.

76. In a vertical type of printing press, the combination of a vertically movable printing cylinder and transfer means movable therewith.

77. In a vertical type of printing press, the combination of a printing couple including a relative rectilinearly movable printing cylinder and type bed and transfer means movable with one member of said couple.

78. In a vertical type of printing press, the combination of a vertical rectilinearly movable printing cylinder and means for feeding material to said cylinder.

79. In a vertical type of printing press, the combination of a printing couple including a relative vertically movable printing cylinder and type bed and means for feeding material to said cylinder.

80. In a vertical type of printing press, the combination of a vertically movable printing cylinder and a transfer table receiving a sheet of material in a given position and movable downwardly preparatory to a passage of said sheet from said transfer table to said cylinder.

81. In a printing press, the combination of a vertically movable printing cylinder, a vertically movable transfer table associated therewith whereby a sheet of material is received in one position of said transfer table and conveyed with said transfer table to another position in which the sheet is fed to the cylinder while relatively at rest.

82. In a printing press, the combination of a printing cylinder, a transfer table associated therewith and means whereby a sheet of material is fed to said transfer table at the time that an impressed sheet of material is being withdrawn from said cylinder.

83. In a printing press, the combination of a substantially vertical bed, an impression

- cylinder cooperating with said bed, means to effect relative reciprocation between said bed and cylinder, means to operate said cylinder, means for holding on said cylinder sheet material to receive an impression, means at one side of the plane of the bed for holding stock, means on the opposite side of said bed for receiving impressed sheets of material, means to convey the sheet material in succession from the stock holding means to said cylinder in position to be held thereon, and means for conveying the impressed sheets in succession from said cylinder to said receiving means, substantially as described.
84. In a printing press, the combination of a printing couple comprising a cylindrical member and a flat member having relative movement in a substantially vertical plane, means to effect relative reciprocation between said cylindrical and flat members, means to operate said cylinder, means for retaining a sheet of material in position as it is receiving an impression, means at one side of the plane of the flat member for holding stock, means on the opposite side of said flat member for receiving impressed sheet material, means to convey sheets in succession from the stock holding means to said couple for receiving an impression, and means to convey impressed sheets of material in succession from said couple to said receiving means.
85. In a printing press, the combination of a substantially vertical bed, an impression cylinder cooperating with said bed, means to effect relative reciprocation between said bed and cylinder, means to operate said cylinder, paper holding means on said cylinder, means to actuate said holding means, a stock table at one side of the plane of said bed, a delivery platform on the opposite side of said bed, means to convey the paper sheets in succession from a pile on said stock table to said cylinder in position to be gripped by said holding means, and means to grasp and carry the printed sheets in succession from said cylinder to and deposit them on said delivery platform, substantially as described.
86. In a printing press, the combination of a substantially upright sliding bed, means to reciprocate said bed, an impression cylinder cooperating with said bed, means to operate said cylinder, paper holding means on said cylinder, means to actuate said holding means, a stock table at one side of the plane of said bed, a delivery platform on the opposite side of said bed, means to convey the paper sheets in succession from a pile on said stock table to said cylinder in position to be gripped by said holding means, and an oscillatory conveyor to grasp and carry the printed sheets in succession from said cylinder to and deposit them on said delivery platform, substantially as described.
87. In a printing press, the combination of a substantially upright sliding bed, means to reciprocate said bed, an impression cylinder cooperating with said bed, means to operate said cylinder, paper holding means on said cylinder, means to actuate said holding means, a stock table at one side of the plane of said bed, a delivery platform on the opposite side of said bed, means to feed the paper sheets in succession from a pile on said stock table to said cylinder in position to be gripped by said holding means, and an oscillatory conveyor fulcrumed on the same side of the bed as said delivery platform and adapted to grasp and carry the printed sheets in succession from said cylinder to and deposit them printed face upward on said delivery platform, substantially as described.
88. In a printing press, the combination of a substantially upright sliding bed, means to reciprocate said bed, an impression cylinder on one side of and cooperating with said bed, means to operate said cylinder, paper holding means on said cylinder, means to actuate said holding means, a stock table and a delivery platform on opposite sides of said bed, means to feed the paper sheets in succession from a pile on said stock table to said cylinder and its holding means, and means to convey the printed sheets in succession from said cylinder across the path of travel of said bed and deposit them on said delivery platform, substantially as described.
89. In a printing press, the combination of a substantially upright sliding bed, means to reciprocate said bed, an impression cylinder on one side of and cooperating with said bed, means to operate said cylinder, paper holding means on said cylinder, means to actuate said holding means, a stock table on the same side of said bed as said cylinder, a delivery platform on the opposite side of said bed, means to feed the sheets of paper in succession from the stock table to the cylinder and its holding means, and means operative above said bed when the latter is near its lowermost position to convey the printed sheets in succession across the path of travel of said bed from said cylinder to said delivery platform, substantially as described.
90. In a printing press, the combination of a substantially upright sliding bed, means to reciprocate said bed, an impression cylinder on one side of and cooperating with said bed, means to operate said cylinder, paper holding means on said cylinder, means to cause said holding means to grasp and release the sheets on the cylinder, a stock table on one side of said bed, means to feed the paper sheets in succession from a pile on said stock table and deliver them to

the cylinder and its paper holding means, a delivery platform on the opposite side of said bed, and means to convey the printed sheets from the cylinder when released by 5 the paper holding means to said delivery platform, such sheets being conveyed to said paper holding means and delivered therefrom while such means are near the upper portion of their travel about the axis of 10 the cylinder, substantially as described.

91. In a printing press, the combination of a substantially upright sliding bed, means to reciprocate said bed, an impression cylinder on one side of and cooperating with 15 said bed, means to operate said cylinder, paper holding means on said cylinder, means to cause said holding means to grasp and release the sheets on the cylinder, a stock table at one side of said bed, a delivery 20 platform at the opposite side of said bed, means to feed the paper sheets in succession from a pile on said stock table and deliver them to the cylinder and its paper holding means, and means to convey the printed 25 sheets from the cylinder when released by its holding means across the path of travel of the bed when the latter is near its lower-most position to said delivery platform, such sheets being fed to said paper holding means 30 and delivered therefrom while such means are in the upper portion of their travel about the axis of the cylinder, substantially as described.

92. In a printing press, the combination of a substantially upright sliding bed, means to reciprocate said bed, an impression cylinder at one side of and cooperating with 35 said bed, means to operate said cylinder, a stock table at one side of said bed, automatically acting means to feed sheets of paper in succession from a pile on said table to said cylinder, paper holding means on said cylinder, means to actuate said holding means, a delivery platform on the 40 opposite side of said bed, and means to grasp and carry the printed sheet freed from said holding means across the path of travel of the bed and before the latter has moved upwardly any substantial distance and deposit such sheets printed face upward on 45 the delivery platform, substantially as described.

93. In a printing press, the combination of a frame with substantially vertical guides, a bed slidable in said guides, means to reciprocate said bed, an impression cylinder 50 cooperating with said bed, means to operate said cylinder, a support hinged to swing in a horizontal plane, a stock table on 55 said support, a transfer table on said support, means on said support to feed the

sheets of paper individually from a pile on said stock table to said transfer table, means to operate said feeding means, side and front gauges, means to lock said support with its 65 elements in cooperative relation with said cylinder, and means partly on said frame to shift said transfer table obliquely when the support is locked to carry the sheet of paper on the transfer table into register 70 with said gauges, substantially as described.

94. In a printing press, the combination of a main frame, a bed substantially vertically slidable in said frame, means to reciprocate said bed, an impression cylinder 75 cooperating with said bed, means to operate said cylinder, a support hinged to said frame and adapted to be swung into and out of operative position, a stock table on said support, a transfer table on said support, means on said support to convey the sheets of paper individually from a pile on said stock table to said transfer table, means on said cylinder to receive the sheets from said transfer table and grip them to the 80 cylinder, a hinged frame adapted to be swung into and out of operative position in a direction different from the swinging movement of said support, one or more form inking rollers on said frame, means to lock 85 said support with its elements in operative relation to said cylinder, and means to lock said frame with its rollers in operative relation to said bed, said frame being disposed inwardly toward the bed with respect to 90 said support when both are locked in operative position, substantially as described.

95. In a vertical type of printing press, the combination of a printing cylinder having a movement substantially in a vertical 100 plane during the impression stroke, and transfer means associated therewith.

96. In a printing press, the combination of a substantially vertical bed, an impression cylinder cooperating with said bed, 105 means to effect relative reciprocation between said bed and cylinder, means to operate said cylinder, means for holding on said cylinder sheet material to receive an impression, means at one side of the plane 110 of the bed for holding stock, means on the opposite side of said bed for receiving impressed sheets of material, means to convey the sheet material from the stock holding means to said cylinder in position to 115 be held thereon, and means for conveying the impressed sheets from said cylinder to said receiving means, substantially as described.

Signed at Chicago, Illinois, this 5th day 120 of March, A. D., 1918.

EDWARD CHESHIRE.

Certificate of Correction.

It is hereby certified that in Letters Patent No. 1,567,177, granted December 29, 1925, upon the application of Edward Cheshire, of Milwaukee, Wisconsin, for an improvement in "Printing Presses," an error appears in the printed specification requiring correction as follows: Page 11, line 30, claim 54, after the word "and" insert the word *means*; and that the said Letters Patent should be read with this correction therein that the same may conform to the record of the case in the Patent Office.

Signed and sealed this 26th day of January, A. D. 1926.

[**SEAL.**]

WM. A. KINNAN,
Acting Commissioner of Patents.
